United States Patent Office

Des. 229,389
Patented Nov. 27, 1973

229,389

ELECTRIC SHEARS

Robert D. Kahn, Rockville Centre, N.Y., assignor to
Fedtro, Inc., Rockville Centre, N.Y.

Filed Oct. 4, 1971, Ser. No. 186,594

Term of patent 14 years

Int. Cl. D8—03

U.S. Cl. D8—61

FIG. 1

FIG. 3

FIG. 1 is a perspective view showing the top, back and left side of the electric shears;

FIG. 2 is a right side view thereof;

FIG. 3 is a front elevational view thereof;

FIG. 4 is a top plan view thereof; and

FIG. 5 is a bottom plan view thereof.

I claim:

The ornamental design for electric shears, as shown and described.
